W. J. TERRY

DENTAL HANDPIECE

Filed Sept. 14, 1923

INVENTOR

Walter J. Terry
Harry Bowen
ATTORNEY

UNITED STATES PATENT OFFICE.

WALTER J. TERRY, OF SEATTLE, WASHINGTON.

DENTAL HANDPIECE.

Application filed September 14, 1923. Serial No. 662,764.

To all whom it may concern:

Be it known that I, WALTER J. TERRY, a citizen of the United States, residing at Seattle, county of King, and State of Washington, have invented new and useful Improvements in Dental Handpieces; and I do hereby declare that the following is a full, clear, and exact specification, such as will enable others skilled in the art to which

10 it appertains to make and use the same.

The invention is the improving of dental handpieces to make it possible to hold the various implements at an angle so that it will be possible to reach the buccal, labial, 15 lingual, mesial, and distal surfaces easily and also the eliminating of corrosion in the handpiece by providing a spindle of non-corrosive material, in the knurling of the metal sheath so that the vulcanite handle 20 may be omitted making it possible to boil the sheath for sterilization and also reducing the grip diameter of the handpiece handle, and in the curving of the edges of the spindle drive pulley to prevent the cutting of 25 the driving cord.

One object of the invention is to provide a means by which the different implements may be held at an angle in relation to the handpiece.

30 Another object of the invention is to provide a means for holding the different implements at an angle which is interchangeable so that any desired implement may be readily held to the handpiece.

35 Another object of the invention is to eliminate corrosion in the spindle.

Another object of the invention is to reduce the diameter of the handle of the handpiece so that it will be possible to have 40 better control over the instrument for delicate work.

And a further object of the invention is to provide a pulley for the spindle which will not cut the driving cord.

45 With these ends in view the invention embodies a dental handpiece of the Doriot style having a phosphor bronze spindle, an all metal sheath, a pulley having a groove with curved edges, an angle attachment having a bearing for the rear shaft separated from the rear case and placed between the two sections which are screwed upon threads at each end of the bearing with the sleeve telescoping over the bearing; and also a combination of chucks for holding mandrels or

50 Other features and advantages of the invention will be seen from following description taken in connection with the drawings, wherein:—

Figure 1 is a side view of a handpiece with part broken away.

Figure 2 is a view showing the spindle.

Figure 3 is a view showing the all metal sheath.

Figure 4 is a sectional view showing the angle attachment.

Figure 5 is a view showing a chuck for holding implements having shanks with pins.

Figure 6 is a view showing a chuck for holding discs.

Figure 7 is a view showing another chuck for holding discs or the like.

Figure 8 is a view showing a screw jaw 75 chuck for holding implements with plain shanks.

In the drawings I have shown my improvements as they would appear in a handpiece of the Doriot style wherein numeral 1 80 indicates the handpiece, numeral 2 the spindle, numeral 3 the sheath or handle, numeral 4 the pulley, and numeral 5 the chuck casing.

The spindle 2 may be made of phosphor bronze or any non-corrosive material and 85 may be made in the design shown in Figure 2 which is similar to spindles used in handpieces of this type. The sheath 3 which surrounds the spindle may be made as shown in Figure 3 and held to the bracket supporting the spindle by a nut 6 as shown in Figure 1. The sheath will have a flange 7 at

its upper end by which it may be held by the nut 6 to the spindle bracket. The outer surface of the sheath is knurled between the 95 points 8 and 9 to provide a gripping surface so that the vulcanite sleeve ordinarily used as a handle may be omitted, thereby making it possible to reduce the diameter of the gripping surface so that it will be possible to obtain a steadier grip for delicate work; and being all metal it can be boiled for sterilization, which is impossible with the ordinary vulcanite grip.

The pulley 4 is provided with a V shaped 105 slot 10, a knurled surface at one side of the slot as indicated by the numeral 11 and a hole in the center through which it is rigidly mounted on the upper end of the spindle. The edges of the V-shape slot are curved as 110 shown at the points 12 and 13 so that as a cord is passed over the pulley and twisted

the edges of the slot or groove will not cut the cord. The knurling only extends for a short distance from the opposite side of the pulley so that it will not roughen the upper edge of the groove. The handpiece is also provided with a lock nut 14 and a long pin which goes through the spindle and which is provided with a thumbnut 15 by which it may be turned, for tightening the implement chuck in the lower end of the spindle. The entire device is supported in a bracket 16 which has a flexible joint at its outer end in which two small idler pulleys 17 and 18, over which the cord passes, are mounted.

15 The angle attachment shown in Figure 4 has a casing 19 that fits over the tip of the sheath 3. The casing is provided with an opening 20 into which the tip of the sheath projects and a slot 21 into which a pin 22

20 on the side of the sheath extends to hold the casing from turning on the sheath. The lower end of the casing is provided with a recess 23 and at the end of the recess is a threaded portion 24 into which a threaded

25 shank 25 on a bearing 26 is screwed to hold the bearings in the end of the casing. The bearing 26 has an opening through its center through which a shaft 27 with a collar 28 made integral therewith and a pinion 29

30 held to it by a pin 30 extends. The upper part of the shaft projects beyond the end of the casing so that it may be gripped in the end of the spindle. The bearing 26 has notches 31 in the sides by which it may be held with a wrench as it is being screwed into the angle sleeve 32. After it is screwed all the way into this sleeve the casing 19 may be screwed on to the shank 25 while the sleeve 32 is held by a wrench which grips it through the notches 33. It will be seen that the pinion 29 meshes with a similar pinion 34 on the chuck spindle 35.

45 The chuck spindle is supported in a casing 5 which has notches in its sides and a threaded shank 36 that screws into a threaded hole 37 in the outer end of the angle sleeve 32. The chuck spindle may be made as shown in Figures 5, 6, 7, and 8 with means at its outer end for holding implements of different types and the pinion 34 held to its inner end by a pin 38.

55 In the design shown in Figure 5 the outer end of the chuck spindle is in the form of a hollow cylinder with slots 39 in its sides and small transverse slots 40 at the inner ends of the former slots so that a shank having pins on the sides may be pushed through the longitudinal slots and then twisted so that the pin will be held in the transverse slot, thus making it possible to drive the implement in either direction.

60 In the design shown in Figure 6 the outer end of the spindle is in the form of a cylinder with an opening 41 through its center into which a wire spring 42 with a cup

shaped head 43 may be pressed to hold paper discs or the like on prongs 44 at the end of the cylinder.

65 In the design shown in Figure 7 the outer end of the spindle is provided with a threaded hole 45 into which a screw 46 may be screwed to hold a disc or the like and the outer end of the spindle may be indented as shown between the points 47 and 48 and also provided with notches 49 by which it 70 may be held with a wrench. The indented portion between the points 47 and 48 will cause emery dust from the grinding wheel to fly outward as it moves backward, thereby, throwing it away from the joint 50. 75 The outer end of the spindle shown in Figure 8 is constructed in the form of a screw chuck with a threaded sleeve 51 having slots 52 in it and a tapering nut 53 which when screwed upon the sleeve will force the jaws 80 inward and positively grip a shank that may be placed therein.

85 It is understood that either of the designs shown may be used with the angle attachment or with a similar straight attachment 90 and also that any other design may be used so that it will be possible to hold a spindle or shank of any design or size.

95 It is also understood that other changes may be made in the construction without departing from the spirit of the invention. One of which changes may be in the design of the spindle, another may be in the design of the sheath, another may be in the design of the angle attachment, and still another 100 may be in the design of the bracket at the upper end of the handpiece.

105 The construction will be readily understood from the foregoing description. To use the device it may be assembled as shown 110 and by placing the attachment shown in Figure 4 over the tip of the sheath it will be possible to hold discs, stones, or the like at a convenient angle for cleaning, grinding and polishing the buccal, labial, lingual, mesial and distal surfaces of the teeth. It will 115 also be seen that by applying an angle attachment of this type the right or contra-angle headpiece may be removed and replaced by removable chucks or mandrels in the form of a unit, comprising the gears, 120 bearings, and mandrel for holding implements such as emery grinding wheels, paper polishing discs or wheels, rubber cleaning cups, cleaning brushes of different forms and also drills and cutting drills. The non-corrosive spindle in the headpiece will permit 125 the handpiece to work freely at all times as the sticking or hard turning of the spindle caused by rust and corrosion will be entirely eliminated.

130 The usual wear or cutting of the driving cords or belts which was caused by the sharp edges of the driving pulley when the handpiece is twisted will also be eliminated as these edges have a smooth

curve. And the bulky holding surface caused by placing a vulcanite sleeve over the sheath will be entirely eliminated as the outer surface of the sheath is knurled to provide a gripping surface. This also permits the sheath to be boiled when sterilized.

It will, therefore, be seen that these improvements not only provide a dental handpiece of the Doriot style of a much higher 10 quality but also make it possible to hold various implements at a convenient angle and with greater accuracy.

It should be further understood that the angular attachment can also be used on 15 other type straight handpieces other than those of the Doriot style as hereinbefore described as it will be noted that the only change required to do so would be in changing measurements and shape of the sleeve 20 19 to correspond to other straight handpiece spindle sheaths.

Having thus fully described the invention, what I claim as new and desire to secure by Letters Patent, is:—

25 1. A dental handpiece having a non-corrosive spindle, a sheath with its outer surface knurled around the spindle, a bracket for supporting the sheath and spindle, means for holding the spindle and sheath in the 30 bracket, means for holding implements in the lower end of the spindle, a pulley at the upper end of the spindle having the inner edges of its grooves rounded and a knurled surface on one side of the groove, other 35 pulleys mounted in a universal joint at the end of the bracket, and a suitable attachment that may be placed on the lower end of the handpiece in which suitable chucks 40 may be placed for holding implements of different types; said attachment being made in two sections which are held together by a collar having threaded shanks on each end that screw into threaded holes in the sections and said collar forming a bearing 45 for a shaft that may be gripped in the lower end of the handpiece spindle so that

it will rotate with it, which shaft has a pinion on its opposite end that meshes with a pinion on the chuck spindle.

2. A dental handpiece of the type described having a non-corrosive spindle, a sheath with a knurled outer surface; a pulley at the upper end of the spindle having the edges of its groove curved; means for supporting the spindle and sheath; other 50 means for rotating the spindle; a sleeve that may be placed over the lower end of the sheath; a bearing that may be placed in the lower end of the sleeve that is provided with a collar that telescopes in the lower 55 end of the sleeve; and a threaded shank at one end of the collar which screws into the sleeve; and another threaded shank at the opposite end of the collar that screws into an angular sleeve; a casing forming a bearing 60 for a chuck spindle that may be screwed into the end of the angular sleeve; and suitable means for rotating the chuck spindle from the handpiece spindle.

3. A device of the class described having 70 a spindle of a non-corrosive material; a sheath surrounding the spindle having its outer surface roughened to form a handle; a pulley at the upper end of the spindle having the edges of its groove rounded; means for supporting the spindle and sheath; means for holding implements in the lower end of the spindle; a sleeve having a shaft in its center that may be placed 75 over the sheath so that the shaft will project into the spindle; a removable bearing with a telescoping sleeve for the shaft in the lower end of the sleeve; another sleeve that may be screwed onto the shank at the outer end of the bearing; a pinion on the 80 outer end of the shaft projecting into the latter sleeve; and a chuck with a pinion on its inner end to engage the former pinion as the chuck is placed in the end of the latter sleeve and a means in its outer end 85 for holding implements.

WALTER J. TERRY.
